(57) **CLAIM**

The ornamental design for a ring and hook wire management system with angled hanger, as shown and described.

DESCRIPTION

FIG. 1 is a front view of a first embodiment of a ring and hook wire management system with angled hanger, showing our new design;

FIG. 2 is a back view thereof;

FIG. 3 is a top view thereof;

FIG. 4 is a bottom view thereof;

FIG. 5 is a left side view thereof;

FIG. 6 is a right side view thereof;

FIG. 7 is a perspective view thereof;

FIG. 8 is a front view of a second embodiment of the ring and hook wire management system with angled hanger;

FIG. 9 is a back view thereof;

FIG. 10 is a top view thereof;

FIG. 11 is a bottom view thereof;

FIG. 12 is a left side view thereof;

FIG. 13 is a right side view thereof;

FIG. 14 is a perspective view thereof;

FIG. 15 is a front view of a third embodiment of the ring and hook wire management system with angled hanger;

FIG. 16 is a back view thereof;

FIG. 17 is a top view thereof;

FIG. 18 is a bottom view thereof;

FIG. 19 is a left side view thereof;

FIG. 20 is a right side view thereof; and,

FIG. 21 is a perspective view thereof.
